UNITED STATES PATENT OFFICE

GEORGE M. PELTON, OF MILWAUKEE, WISCONSIN, ASSIGNOR TO THE FILER & STOWELL CO., OF MILWAUKEE, WISCONSIN, A CORPORATION OF WISCONSIN

SAWMILL CARRIAGE

Application filed November 12, 1929. Serial No. 406,666.

This invention is directed to an improvement in means for limiting the movements of the dogs of a saw mill carriage to prevent the dogs from reaching the saw line without in any way interfering with the usual limit travel of the knee toward the saw line.

The invention is particularly applicable to that type of dogging mechanism in which the dogs are adapted for either a minimum projection beyond the face of the knee or a maximum projection beyond the face of the knee, the position of the dogs being manually controlled and adjusted at will to suit the particular conditions of dog use. Obviously, where the dogs are capable of minimum or maximum projection beyond the face of the knee, any means to limit the movement of the dogs toward the saw line to thereby prevent the dogs from entering the saw line must take into consideration the different relative positions of the dogs relative to the face of the knee, for if the knee was interrupted in its travel toward the saw line so as to prevent the dogs at their minimum projection from being engaged by the saw, obviously the dogs when projected to their maximum degree would reach the saw line before the forward movement of the knee was completely interrupted. Conversely, if the knee interruption was provided for to take care of the dogs when projected their maximum distance beyond the face of the knee, the knee travel would be stopped long before the dogs when at their minimum projection could enter the saw line. Thus, no positive stop cooperating with the knee alone can properly take care of both conditions.

The invention is more particularly concerned with that type of dog operating mechanism wherein a frame, by which the dogs are carried and on which they are relatively vertically movable for the dogging operation, is mounted for movement toward and from the face of the knee, so that the dogs carried by the frame may be projected to greater or

lesser distances beyond the face of the knee to provide for effective dogging action in the particular instance. Ordinarily the frames are supported on cranks mounted in or on the knee and, by reason of such cranks, the frames are advanced toward and from the face of the knee.

In my co-pending application Serial No. 348,322, filed March 19, 1929, I have shown a dog limiting means in the form of a rigid arm extension from one of the operating cranks for the frame, with this arm extension cooperating with a stop on the head block to limit the movement of the dogs relative to the saw line without regard to the degree of projection of the dogs beyond the face of the knee as controlled by the frame. Such rigid construction, however, while effective, will necessarily, owing to its relatively angular movements under frame adjustment, cooperate with the fixed stop of the head block at different angles, and while nevertheless effective as a stop, does not present that effective abrupt control of the dogs advisable in a construction of this kind.

The primary object of the present invention, therefore, is to provide a dog limiting element which is directly positioned for dog control operation in the adjustment of the frame by which the dogs are moved to their minimum or maximum projection beyond the face of the knee, with this dog limiting means so mounted as to remain in all possible positions of the frame with its operating stop or free end at substantially right angles to the head block stop to insure the most effective and least wearing operation of the parts in service.

The invention, more particularly described, includes an element mounted on and for movement with respect to one of the frame supporting cranks, so that as the crank is moved to operate the frame, the stop element is correspondingly moved. The stop element, however, is connected through

an individual crank mounting with the knee, this individual crank mounting remaining in parallelism with the crank cooperating with the frame, so that the stop element remains at all times in a predetermined position with respect to the plane of the stop carried by the head block while at the same time shiftable with the frame as the latter is operated to position the dogs relative to the face of the knee.

10 The invention is illustrated in the accompanying drawings, in which:

Figure 1 is a broken view in elevation, showing the improved construction.

15 Figure 2 is an enlarged perspective view, showing the lower crank mounting for the frame and the connection therewith of the improved stop element.

Figure 3 is a view showing the lower crank 20 mounting.

In the form illustrated, the knee 1, movable on and with respect to the head block 2, is provided with a frame 3, preferably in the form of a bar-like element, with this frame 25 supported on upper and lower cranks 4 and 5 mounted in the knee. The dogs, indicated at 6, are movable longitudinally of the frame and relative to each other for the dogging operation, it being understood that means, 30 preferably power means, are provided for shifting the frame and thereby the dogs with respect to the face of the knee, and further means, preferably power means, are provided for moving the dogs relative to each other 35 and with respect to the frame for the dogging operation. This construction is more or less conventional and well understood and only sufficient thereof is illustrated to give a comprehensive understanding of the specific improvement relative to the stop element.

It will be appreciated that the log or cant, held to the face of the knee by the dogs, is advanced toward the saw at each successive sawing operation and that if the dogs have been projected to their maximum distance, it is quite possible, in the absence of a protecting means, that the dogs will cross the saw line in advance of the knee. This liability of the dogs encroaching upon the saw line is 50 practically present in any possible log or cant holding position of the dogs, for while it is conventionally understood that the knee is limited in its movement on the head block, so that such knee cannot cross the saw line, yet the limit approach of the knee to the saw line is, in order to provide for effective board sawing, so close to such saw line that any substantial projection of the dogs would project said dogs, in the absence of limiting means, 55 into the saw line. Of course, a limiting means to be effective must permit the dogs to remain in the log or cant with full holding effect up to a point immediately short of the saw line and as this limiting position of the dogs will, of course, materially vary in ac-

cordance with the projection of the dogs beyond the face of the knee, it is apparent that the limiting means, in its effective application, must in itself compensate for the different positions of the dogs beyond the face of the knee and must be effective to interrupt the movement of the dogs with the knee as said dogs approach the saw line, no matter what the projection of the dogs beyond the face of the knee may be.

70 In the application above referred to, the limiting means is shown as a rigid extension of one of the cranks, the free end of which extension is designed to cooperate with the stop on the head block. In this form, the rigid connection or arm will, of course, move with the crank which controls the movement of the frame, that is, the position of the rigid connection or arm will be moved in correspondence with the projection of the dogs 75 with respect to the face of the knee. As this arm, however, is a rigid extension of one of the cranks, the angular relation of the frame end of the arm with respect to the stop on the head block varies in the different positions of the arm, and this is objectionable both from the standpoint of undue wear and the further objection of the angular relation of the arm and stop, tending to a somewhat less effective interrupting influence 80 than where comparatively broad portions or surfaces of the stop and extension are brought into flat contact for stopping purposes.

85 In carrying out the present invention, the shaft 7 forming part of the lower crank 5, which is mounted in the spaced walls of the knee, is provided beyond one surface of the knee with a crank extension 8 which, being rigid with the shaft 7, is in exact correspondence with the crank 5 in the movement of the frame. Pivotaly supported at the lower end of the crank extension 8 on an appropriate pin 9 is an L-shaped lever 10 having one arm 11, hereinafter referred to as the stop arm, and a lateral arm 12 terminally and pivotally connected at 13 to a link 14 pivotally supported at 15 on the knee.

90 The link 14 and crank extension 8 are 100 similar in length and their respective mountings and the length of the arm 12 are such that the crank extension 8 and link 14 remain parallel in all movements of the crank extension 8. The lower end of the stop arm 11 is turned downwardly to present a vertical extension 16, and an adjustable stop element 17 is threaded transversely with the portion 110 of the stop arm. A stop 18 is arranged 115 on the head block 2 in the path of movement 120 of the stop element 17.

125 In the adjustment of the frame to project the dogs to the minimum distance beyond the face of the knee, as indicated at 19, it will be apparent that the crank 8 assumes the full line position and that by reason of the link 130

14, the stop arm 11 is, while moving in response to the movement of the crank 8, nevertheless held so that its stop element 17 forms a square abutment to directly and flatly engage the stop 18 on the head block. If the frame has operated to adjust the dogs to their maximum position, as indicated at 20, the free end of the crank 8 will, of course, move toward the face of the knee, but by reason of the crank link 14, the angular relation of the arm 12 to the plane of the head block will not be altered and hence the stop arm 11 is maintained in exactly the same position as in the previous arrangement of the dogs, that is, with its stop element 17 providing a square abutment for the head block stop 18.

Thus, by reason of the mounting of the stop element 10, the stop arm 11 is maintained in the same angular relation with respect to the head block in all adjustments of the dog carrying frame relative to the face of the knee. Therefore, in any position of the stop arm, there is the maximum effective stop contact between the adjustable stop element of said arm and the head block stop.

Of course, it is understood that when the stop element 17 of the stop arm 11 cooperates with the stop 18 on the head block and the knee continues to advance, the dogs, by reason of the rearward shifting of the frame with respect to the face of the knee, are gradually withdrawn from their then projected position. That is to say, the movement of the dogs is interrupted at a point before such dogs would otherwise cross the saw line and the dogs can no longer advance with the knee and there is no possibility of damage resulting from the dogs crossing the saw line.

The effective function of the stop arm held at all times at substantially right angles to the head block insures not only an effective cooperation of the stop arm with the head block stop but maintains exactly this same cooperation during the further advance of the knee and during the withdrawal of the dogs. Where the stop arm is a rigid portion of the crank, the angular relation of said arm is continually changed as the crank moves relative to the knee during the withdrawal of the dogs, and thus there is at best a slight sliding cooperation between the stop arm and head block stop while the dogs are being withdrawn in those forms where the projection or stop arm is rigid with the crank.

In the present form, however, the position of the stop arm with respect to the head block, that is, the relative angular relation of these parts, is at all times constant and does not change in the relative movements of the cranks either for positioning the dogs or in the automatic withdrawal of the dogs through the stop cooperation. Therefore, the stop is not only absolutely effective as a

limiting means for the movement of the dogs toward the saw line but insures that the dogs, when once interrupted, will not be permitted further advance movement even to the slightest degree, for the contact between the stop arm and head block stop is at direct right angles to the plane of movement of the knee, and remains in such relation in all possible positions of the parts. This result, of course, is secured by reason of the fact that the stop arm proper is mounted for free rotation with respect to the frame operating cranks but is controlled in this rotation by a crank having an exactly corresponding movement to that of the frame crank. This parallel motion of the cranks insures that the stop arm will remain in exactly the same position with respect to the head block in all relative positions of the frame operating crank.

What is claimed to be new is:

1. In a saw mill carriage, a knee, a dog mounting, cranks connecting the dog mounting and knee to permit movement of the mounting toward and from the face of the knee, dogs carried by the mounting, a stop on the carriage, an arm carried by one of the cranks to cooperate with said stop in the movement of the knee toward the saw line, and means positively connecting said arm and knee to maintain successive positions of said arm substantially parallel with one another.

2. In a saw mill carriage, a knee, a dog mounting, cranks connecting the dog mounting and knee to permit movement of the mounting toward and from the face of the knee, dogs carried by the mounting, a stop on the carriage, an arm carried by one of said cranks and bodily movable longitudinally of the knee, and means positively connecting the arm and knee to cause the successive positions of the arm to be substantially parallel one with the other, a stop carried by the arm to engage the stop on the carriage, the successive parallel positions of the arm maintaining the stop on the arm in position to directly engage the stop on the carriage in all positions of the arm.

3. In a saw mill carriage, a knee, a dog mounting, cranks connecting the dog mounting and knee to permit movement of the mounting toward and from the face of the knee, dogs carried by the mounting, a stop on the carriage, an arm for cooperation with said stop, said arm being movably carried by one of the cranks to insure bodily movement of the arm longitudinally of the knee in the movement of the crank, and link mechanism connecting the arm and knee to maintain the arm in a substantially vertical plane with respect to the knee during such bodily movement.

4. In a saw mill carriage, a knee, a dog mounting, cranks connecting the dog mounting and knee to permit movement of the

mounting toward and from the face of the knee, dogs carried by the mounting, a stop on the carriage, an angle lever movably supported by one of the cranks and bodily movable longitudinally of the knee in response to crank movement, one arm of said lever forming a stop arm to cooperate with the carriage stop, and a link connecting the free end of the remaining arm with the knee, said link 10 serving to maintain said arm in a substantially vertical position with respect to the knee throughout the bodily movement of the angle lever responsive to crank movement.

In testimony whereof I affix my signature.
